UNITED STATES PATENT OFFICE.

DWIGHT MURPHY, OF PITTSBURGH, PENNSYLVANIA.

HOOD-CAP FOR OUTSIDE METAL CAR-ROOFS.

1,081,323.

Specification of Letters Patent.

Patented Dec. 16, 1913.

Application filed May 23, 1913. Serial No. 769,377.

To all whom it may concern:

Be it known that I, DWIGHT MURPHY, a citizen of the United States, and a resident of the city of Pittsburgh, county of Allegheny, and State of Pennsylvania, have invented a new and useful Improvement in Hood-Caps for Outside Metal Car-Roofs, of which the following is a specification.

This invention relates to means for covering the open ends of the standing seams connecting the roof sheets of outside metal car roofs and for securing the eaves corners of the roof sheets upon the roof substructure. Heretofore, malleable iron castings have been used to cover the open ends of the seams and to secure the eaves corners of the roof sheets upon the substructure, but a cast iron hood cap as heretofore made is objectionable for the reason that its lower surface, which is rough and uneven, comes in contact with the roof sheets. The continual movement of the roof sheets on the roof substructure when the car is in motion causes incessant rubbing contact between the corners of the roof sheets and such hood caps, and results in wearing the galvanizing off the corners of the sheets so that these are the first places to rust out and fracture.

The object of this invention is to prolong the life of the roof sheets by overcoming the tendency of metal hood caps to wear out their corners. In carrying out this object the hood cap is provided with means for spacing it above the corners of the roof sheets in such a way that the latter cannot come in contact therewith. Furthermore, the hood cap is made of sheet metal which has a smooth surface not likely to wear the galvanizing off the roof sheets. The sheet metal hood cap also has a certain amount of resiliency enabling it to spring or give slightly in response to distortion of the roof substructure.

Further objects of the invention relate to the manner of forming the sheet metal hood cap shown in the accompanying drawings, and to the details of construction thereof.

The novel features of the invention appear more fully in connection with the following description thereof, and the essential features are defined with particularity in the appended claims.

In the drawings, in which like characters designate like parts in the several views,— Figure 1 is a vertical transverse section

through the eaves of a car embodying my invention, showing a hood cap in side elevation; and Fig. 2 is a top view; Fig. 3 a longitudinal section and Fig. 4 a side elevation, of the hood cap.

Referring to the drawings, in Fig. 1 the hood cap 11 is illustrated as applied to a car roof similar to that shown in Patent No. 1,039,401, although the invention is applicable to outside metal car roofs of other forms than the one shown in said patent. Preferably, however, the roof sheathing 12 is nailed crosswise on the top of the car, and the eaves ends of the boards rest directly upon the side plate 13 and project outwardly beyond it, covering the tops of the side sheathing 14 and top of the fascia board 15. A shallow rabbet 16 is cut in the top side of the eaves ends of the roof boards within which the interlocked rebent ends 17, 18 of the roof sheets 19 and flashing strip 20 lie. The flashing strip is bent down over the eaves to cover the joint between the roof boards and the fascia board, and is nailed to the latter. Hood caps are securely fastened on the fascia board outside of the flashing strip by means of bolts 21 and nails 22 or other securing means. These hood caps are placed over the ends of the standing seams 23 or joints connecting the roof sheets, and they limit the vertical movement of the roof sheets at these points.

The hood cap has a hood portion 24 which is wider than the standing seams between the roof sheets, but its inside vertical dimension is slightly less than the height of the seam above the roof sheets. The side walls 25 of the hood portion terminate in laterally extending flanges 26 which are slightly rounded on their under sides. The end wall 27 of the hood portion is extended downward and widened to form a connecting plate 28 between the hood portion and the base portion 29 which is secured to the side of the car. Stiffening ribs 30 are formed in the lateral flanges 26 and in the connecting plate and base portion, and these ribs are continued around the angle between the lateral flanges and connecting plate to brace and strengthen the hood cap in the angle.

The connecting plate below the end wall is sheared or punched out on three sides to form an opening 31 and the metal punched out is bent inwardly to form a projecting ledge 32 or shelf beneath the hood portion. This shelf is spaced below the underside of

the top of the hood portion at such a distance that when the hood cap is arranged on the roof over the end of a seam, with the ledge in contact with the eaves board, a slight space is left between the top of the seam and the underside of the hood. A 5 slightly greater space is left between the lateral flanges 26 and the roof sheets than between the top of the seam and underside 10 of the hood portion, so that in case the sheets rise off the roof the top of the seam will come in contact with the hood cap before the corners of the sheets come in contact with the underside of the flanges. Consequently, there can be no rubbing between 15 the underside of the hood cap and the corners of the sheets.

In case the standing seam becomes mashed down to such an extent that the hood cap 20 flanges contact with the roof sheet corners, there is less likelihood of wearing off the galvanizing from the sheets than would be the case if the hood cap were made of malleable iron, because the surface of the sheet 25 metal hood cap is smoother than the malleable iron hood cap. The spacing ledge or shelf 32 is made long enough to provide a good bearing lengthwise of the eaves in order that there may be no pivoting or tilt- 30 ing of the hood cap upon the bolt 21, which would result in bringing one or the other of the lateral flanges into contact with the roof sheets.

Above the bolt hole 33 in the base portion 35 of the hood cap the sheet metal is pressed outwardly in the form of a crescent 34 in order to deflect any water which may trickle down the outside of the hood cap and prevent its passing through the bolt hole and 40 thus into the car. The metal surrounding the bolt hole is bossed outwardly to form a spring seat 35 for the bolt head.

Although the hood cap shown is the preferred form of the device, this invention is 45 not restricted thereto; and the invention is

not restricted to the particular type of outside roof or form of standing seam shown in the drawing.

I claim as my invention:

1. A sheet metal hood cap having a base 50 portion provided with an opening for a securing member, the metal surrounding said opening being spaced above and at an angle to the plane of said base portion to form a spring seat for said securing member, the 55 high side of said spring seat being toward the hood and the metal immediately adjacent thereto at the side thereof toward said hood being pressed up to form a watershed for said opening.

2. A hood cap for a car roof comprising metal roof sheets joined by raised seams terminating short of the eaves, said cap having a hood portion adapted to span a seam and close its open end and a base portion adapted 65 to be secured to the side of the car, said base portion being provided with an inwardly projecting shelf adapted to bear upon the top of the car, between the end of a hollow seam and the eaves, said shelf being of a 70 length not less than the width of the hollow seam with which it is adapted to coöperate.

3. A hood cap for a car roof comprising metal roof sheets joined by raised seams, said cap having a hood portion adapted to 75 span a seam and a base portion adapted to be secured to the side of the car, said hood portion having lateral flanges spaced below its top a distance slightly less than the height of said raised seams, and said base 80 portion being provided with an inwardly projecting shelf adapted to bear upon the top of the car, said shelf being spaced below the plane of the lower faces of said flanges.

Signed at New Kensington, Pa., this 19th 85 day of May, 1913.

DWIGHT MURPHY.
